Patented Oct. 18, 1921.

UNITED STATES PATENT OFFICE.

GERARD R. MARSICO, OF BROOKLYN, NEW YORK, ASSIGNOR TO PURITON MANUFACTURING CORPORATION, OF BROOKLYN, NEW YORK, A CORPORATION OF NEW YORK.

SIGNAL.

1,393,899.

Specification of Letters Patent.

Patented Oct. 18, 1921.

Application filed June 9, 1919, Serial No. 302,742. Renewed August 27, 1921. Serial No. 496,164.

To all whom it may concern:

Be it known that GERARD R. MARSICO, citizen of the United States, and resident of Brooklyn, in the county of Kings and State 5 of New York, have invented certain new and useful Signals, of which the following is a specification.

This invention relates to signals and more particularly to that type shown in my application Serial No. 242,445, filed June 28, 1918.

In my co-pending application above identified, use is made of a heavy rotor having an interior annular clutch surface and a revolving hanger carrying clutch devices 15 adapted to be canted and brought into active clutch engagement with said interior annular surface so that motion imparted to the hanger will be transferred to the rotor when the former is revolved in one direction. The 20 interior annular clutch surface is located adjacent to the periphery of the rotor so as to increase the leverage action of the clutch devices thereagainst and cause frequent pulsations or disturbances in the diaphragm, while 25 increasing the intensity of the sound produced. In the improvements which will be presently described in detail, I have provided an arrangement somewhat similar to the one described above but functionally operable to create a more positive clutching 30 contact between the respective clutch elements and thus insure quicker action of the rotor against the diaphragm and in fact synchronize the action of the rotor with that 35 of the power transmitting mechanism and thereby cause sound to be immediately created through vibrations of the diaphragm.

I have also simplified the construction and arrangement of parts so as to materially 40 lessen the cost of manufacture of the device while designing such parts for the purpose of establishing quick and positive action and one which will work with minimum resistance.

The various important features will be 45 particularly pointed out hereinafter in connection with a detailed description of a preferred embodiment of my invention which I have selected for illustration in the accompanying drawings, in which similar reference characters indicate corresponding parts 50 in the several views.

In the drawings,

Figure 1 is a vertical longitudinal section

through the device with parts broken away 55 and parts in section.

Fig. 2 is an enlarged view of the rotor showing the movable clutch devices in active clutching positions in full line and in inactive positions in dotted lines. 60

Fig. 3 is a vertical section through the rotor and its hollow support.

Fig. 4 is a vertical transverse section taken substantially on the line 4—4 of Fig. 3 and, 65

Fig. 5 is a vertical section taken substantially on the line 5—5 of Fig. 3.

In carrying the invention into practice use is preferably made of a case 6 having a resonator 7 and at the juncture of the latter with one end of the case is a diaphragm or 70 vibratory member 8 of usual well known construction and provided with a wear piece or anvil 9.

Within the case and secured thereto by screws or the like 10 is a plate 11 having 75 a plunger guide 12 and parallel bracket extensions 13—13. Mounted in said extensions 13—13 is a stationary axle 14 on which is loosely mounted a revoluble support 15.

The support 15 is provided with a gear 80 surface 16 and at one side of said surface is a reduced cylindrical extension 17 and on said extension is loosely mounted a heavy rotor 18 having an external anvil striking surface 19 and an internal clutch surface 20. 85

At the side of the cylindrical extension and formed as a part of the mentioned support 15 is an extension 21 having key or flat faces 22—22. This last named extension projects through a corresponding opening 23 in a 90 disk like body or hanger 24. It will be observed from this construction that said body or hanger is adapted to rotate with the support 15.

In the body or hanger at diametrical opposite positions are recesses 24 having 95 relatively diverging walls 25 and 26 connected by an inner curved wall 27. In the recesses are mounted rigid clutch devices 28 which may be formed of metal, fiber or the like and as shown the width of each of these 100 devices is less than that of the recess in which it is mounted so that it can freely rock or oscillate in said recess. The width of each of these devices increases in the direction of the clutch surface 20 of the rotor 105 18 and at the outer end said devices are provided with arcuate surfaces 29 adapted when the devices are in clutching positions to uni-

formly engage with said surface 20 and establish positive contact therewith as will be observed upon reference to Figs. 1 and 2.

The small gear surface 16 of the support 5 meshes with a gear wheel 30 on a driven shaft 31, the latter carrying a pinion 32 which meshes with the rack surface 33 of a sliding plunger 34. The plunger is yieldingly held in a starting or elevated position 10 by means of a spring 35, one end of which is seated against one end of the plunger and the other end against the adjacent wall of the case 6. The plunger is recessed at one side as at 35, the base wall of which constitutes a stop which co-acts with a lug 36 carried by the plate 11. This arrangement serves to prevent casual separation of the plunger from the mating pinion 32.

Having described the essential features 20 of construction of the device its operation is as follows:

When the plunger is pressed downward against the action of the spring 35, power therefrom will be transferred to the pinion 25 32 and thence to the revolving support 15 which carries the free rotor 18 and the fixed body or hanger 24. Concurrently with this 30 operation the clutch devices 28-28 are swung by centrifugal action against the smooth annular clutch surface 20, the side walls 37 of said clutch devices being brought in flat contact with the walls 26 of the recesses 24. Under this action the rotor becomes fixed to the revolving support 15 and 35 both are moved together on actuations of the plunger 34. On the return movement of the plunger, the active force thereof having been spent, the relative positions of the clutch devices 28 and the surface 20 automatically change and said devices are 40 brought into engagement with the walls 25 of said recesses 24 so that the surfaces 29 of said devices are free with respect to the mentioned annular surface 20. This cycle 45 of events gives initial impetus to the rotor and successively renders the rotor free to permit it to revolve by inertia against the diaphragm. The positive and quick action of the clutch mechanism should be appreciated, when used in connection with a heavy 50 rotor of the design described and by using clutch devices of long and rigid construction and causing the same to co-act with the remote surface 20 or a surface at or near 55 the periphery of the rotor, high power will be quickly created in the rotor to instantly disturb the diaphragm and produce sound of high intensity and amplitude, the freeing of the rotor from the driving mechanism 60 permitting the rotor to spend its entire energy against the diaphragm.

In order to permit of free rocking motion of the clutch device 28, the inner ends thereof are curved to correspond with the walls 65 27 of the recesses 24'. The walls 25 and 26

of said recess serve also to encourage movements of the devices 28 to active clutching positions. When said devices 28 are in the dotted line positions shown in Fig. 2, it will be observed that only small portions of the 70 surfaces 29 contact with the surface 20 so as to reduce friction between such parts. A disk 39 on the extension 21 serves to hold the devices 28 against displacement from said reserves 24'. 75

While I have herein fully shown and described, and have pointed out, in the appended claims certain novel features of construction, arrangement, and operation which characterize my invention, it will be understood by those skilled in the art that various omissions, substitutions, and changes in the forms, proportions, sizes, and details of the device, of the materials used, and of their operation may be made 85 without departing from my invention.

What I claim as new is:

1. In a device of the class described, a vibratory member, a rotor co-acting with said member, said rotor having an annular internal clutch surface, a revolving body independent of said rotor, a rocking clutch element mounted on the revolving body and extending radially from a point near the supporting axis of the rotor to a point near 90 said internal clutch surface and adapted to co-act with the clutch surface, said body having a portion adapted for rigid engagement with the clutch element when the latter is in one position and serving to hold the 95 element in clutch contact with said surface, and means for revolving said body.

2. In a device of the class described, a vibratory member, a rotor co-acting with said member, said rotor having an internal annular clutch surface, a revolving body independent of said rotor, said body having spaced faces defining an intervening recess therebetween, a clutch element mounted to rock in said recess and extending radially from a point near the supporting axis of the rotor to a point near 105 said internal clutch surface and adapted to engage with one of said faces to hold the clutch element in a rigid position and in driving contact with 110 said annular clutch surface, and means for driving said body.

3. In a device of the class described, a rotor, a vibratory member co-acting with the rotor, said rotor having an annular clutch surface, a revolvably supported body having a recess therein, a clutch element mounted to rock in said recess, said element extending radially from a point near the axis of the rotor and in the direction of the 120 annular clutch surface and adapted to engage therewith, the recess having spaced walls serving to respectively render the element operative and inoperative with respect to the annular clutch surface and one 125 130

of said surfaces operating to maintain said element in a relatively fixed position and in clutch contact with said annular surface when the body is rotated in one direction, 5 and means for revolving said body.

4. In a device of the class described, a rotor, a vibrating member, the rotor having a striking surface co-acting with the vibrating member, said rotor having an annular 10 clutch surface near said striking surface and remote from the axis of the rotor, a revolu-

bly mounted body, said body having a recess therein, a rigid clutch element having its inner end mounted in said recess for free rocking motion, and having an outer portion adapted to co-act with said clutch surface when the body is rotated in one direction, and means for rotating said body. 15

Signed at Brooklyn in the county of Kings and State of New York this 29th day 20 of May A. D. 1919.

GERARD R. MARSICO.
